COMBINED SOFA OR SETTEE AND POOL OR BILLIARD TABLE.

APPLICATION FILED MAY 3, 1906.

2 SHEETS—SHEET 2.

UNITED STATES PATENT OFFICE

JACOB N. MCINTIRE, OF NEW YORK, N. Y., ASSIGNOR TO THE BRUNSWICK-BALKE-COLLENDER COMPANY, A CORPORATION OF OHIO.

COMBINED SOFA OR SETTEE AND POOL OR BILLIARD TABLE.

No. 831,293.

Specification of Letters Patent.

Patented Sept. 18, 1906.

Application filed May 3, 1905. Serial No. 258,600.

To all whom it may concern:

Be it known that I, JACOB N. MCINTIRE, a citizen of the United States, residing in the city of New York, in the county of New York and State of New York, (whose post-office address is Box 1089, New York city,) have invented certain new and useful Improvements in a Combined Sofa or Settee and Pool or Billiard Table, of which the following is a specification, reference being had to the accompanying drawings, forming a part thereof.

My invention relates to that article of furniture known as a "combined or combination sofa or settee and pool or billiard table," in which there is one main part which constitutes the seat and end portions (or arm-like parts) of a settee and another main portion which when adjusted in one position relatively to the first-named part constitutes the back portion of the sofa or settee and when adjusted into another (horizontal) position serves the purpose of a game-table. In this type of article or in the piece of furniture above described as heretofore made, used, and patented various constructions have been adopted, none of which, however, so far, according to my information, has resulted in a very desirable and perfectly satisfactory thing, either from a commercial or from a mechanical point of view.

In some of the combination sofa-tables the construction is such that when the parts are adjusted for use as a game-table the bed of the table is not maintained in a sufficiently firm or rigid condition for the playing of the game thereon, while in others in which this difficulty does not exist to a very great extent the structure is such that the translation of the parts or the transformation of the article from a settee to a game-table, and vice versa, cannot be easily or conveniently made where the bed of the table is made (as all approved beds must be) with slabs of slate, which add very much to the gravity or weight of the game-table portion of the piece of furniture. In still other constructions there is too much complexity of mechanism and too great a cost of manufacture to render the piece of furniture commercially successful.

I propose by my invention to provide for use a combination settee or sofa and pool or

billiard table of such construction that, while it may be manufactured at reasonable cost and will in practice be perfectly satisfactory in operation from a mechanical point of view, it will also be very easy of transformation from the sofa to the table, and vice versa, notwithstanding the necessary great weight of the game-table portion of the piece of furniture, which when made with its bed having slate slabs and in the most approved form will usually weigh—in a table, for instance, three and a half by seven feet—some three hundred or four hundred pounds.

To these main ends and objects my invention consists in a combined settee or sofa and pool or billiard table involving the novel construction or the novel combinations of parts, which will be hereinafter fully described, and which will be most particularly pointed out in the claims of this specification.

To enable those skilled in the art to which my improvement relate to make and use the combination piece of furniture comprising my invention, I will now proceed to fully describe the construction and operation thereof by reference to the accompanying drawings, which form part of this specification and in which I have shown my invention carried out as to the various details of construction in that precise form in which I have so far successfully practiced my invention, although it will be understood that with reference to some of the structural features mere modifications or colorable variations may be made without departing from the spirit of my invention.

In the drawings, Figure 1 is a perspective view of my improved article of furniture with its two main portions so relatively adjusted as to adapt it or in that relative position which adapts the article for use as a sofa or settee, and in this figure I have shown a certain hinged or movable arm-piece in its proper position or condition at the right-hand end of the figure, while at the left-hand end I have shown this hinged arm turned into the position to which it has to be adjusted in order to translate the bed portion or back part of the sofa into a horizontal position to adapt the article for use as a game-table, and I have also in this figure shown certain detachable pieces or parts at the left-hand side of the figure removed, as they have to be, to permit the

translation of the sofa back into a horizontal position to transform the article from the sofa into the game-table. Fig. 2 is a perspective view of the combination article or piece of furniture with its two main portions adjusted or placed relatively in the positions in which they have to be to use the article as a pool or billiard table. Fig. 3 is a vertical cross-section taken in a plane indicated by the dotted line 33 at Fig. 1. Fig. 4 is a similar sectional view taken at the dotted line 44 of Fig. 2. Fig. 5 is a partial vertical longitudinal section taken in a plane indicated by the dotted line 55 at Fig. 2 to show particularly the metallic shaft and certain grooved wheels, &c., and the arrangement of these parts with the bed-frame and the tracks located at the upper portions of the arm-like parts of the sofa. Fig. 6 is a detail view (drawn on a somewhat enlarged scale) showing more particularly the structure of the rear end portion of one of the wheel-tracks and the means employed for locking the bed thereto, as will be presently described. Fig. 7 shows in side elevation and top view, on an enlarged scale, one of the metallic track-rails detached. Fig. 8 is a detail view showing how track-wheel is fastened on its shaft.

In the several figures of the drawings the same part will be found always designated by the same letter of reference.

B B are the two end pieces, and C is the seat of the sofa or settee, which parts are framed together in a manner about as usual, as clearly shown, with securing-bolts c^2 and wedge-keys c , which draw and firmly hold together each end of the said seat portion C and each one of the two end pieces of the settee.

The game-table portion of the piece of furniture, which as a whole is lettered A, is composed of a bed-frame A', on which are mounted and to which are secured the usual slate slabs A ^{2} , that are finally covered with the ordinary green or billiard cloth, all in substantially the usual manner of making a billiard or pool table bed, and at a^3 are shown the cushion-rails carrying the billiard or pool table cushion a^4 , all in a manner well known, while in the case shown, the game-table preferably being designed for use as a pocket-table, there are formed at each corner of the bed and in the middle of each one of its two longer sides pockets a^5 of the ordinary construction.

What has so far been remarked as the "table-bed," comprising the usual frame with its slate slabs, is, it will be seen, supplemented beneath or at the lower surface of the bed-frame proper with two cross-beams a^2 a^3 , in which is mounted to freely rotate in suitable metallic bearing-boxes a^7 (see Fig. 5) the metal shaft E, which carries two peripherally-grooved wheels D, mounted fast thereon, all as plainly shown, while a is a board bottom to the bed structure, which when the latter is turned into its substantial vertical position

constitutes the wooden back of the settee or sofa, and a sort of apron-like wooden casing a^6 incloses or closes up the space between the interior of this bottom board a and the bottom surface of the bed-frame proper, A'. 70

As shown, each one of the grooved wheels D just referred to is simply made fast to the shaft E, on which it is mounted by a securing-pin d , (see Fig. 8,) though, if found desirable or expedient, one of these wheels may be combined with the said shaft in such way as to be capable of a slight endwise movement on the latter, which may be necessary in the possible event of the track-rails on which said wheels run getting slightly out of parallelism in consequence of some slight warpage of the wooden portions of the settee part of the piece of furniture on which said track-rails are mounted. 80

G G are two metallic rails or wheel-tracks, each of which is of the peculiar shape or conformation shown in the drawings and which is let down into the woodwork of the upper end of the arm-like portion B of the sofa, to which it is securely fastened by screws or otherwise. 85

As will be readily seen, the bottom board a of the table-bed is cut away or cut through at each of the localities marked a' to permit a slight protrusion through this bottom board of each one of the grooved wheels D, while at H there is preferably let into and secured to said bottom board of the table-bed a small caster-wheel H, which also slightly protrudes through or projects outwardly from the exposed face of the bottom board a , that serves as the back of the settee. (See Fig. 1.) 95

Each one of the track-rails G is formed at its rear end with a curved upwardly-projecting portion G', and each one of these rails is also formed with two depressions—one at g , near its middle, lengthwise, and the other at g^2 , near one of its ends—the purpose of which depressions is to permit the descent thereto, respectively, of one of the grooved track-wheels D and one of the little caster-wheels H, before referred to. 100

I is a pin-fastener or bolt-like device provided with a diametrically-arranged stop-pin i , which fastener-pin is arranged as clearly shown, (see Figs. 4 and 6,) and is accessible through an opening a^8 in the bottom board a of the table-bed, so that it may be manipulated by hand, either to push it in the proper direction to operate as a stop in front of the upwardly-projecting rear end G' of the rail-track G, as seen at Fig. 4, or to retract it so as to leave this upper end G' of the track-rail free to move relatively to the table-bed, when it shall be necessary to move the latter horizontally from its operative condition as a table-bed into position as a sofa-back, as will be presently explained. The aperture a^8 is made in the bottom board a of the bed part of the piece of furniture, through which said 115

120

125

130

locking-pin is readily accessible for the necessary manipulation thereof by hand, as clearly seen at Fig. 6.

The rear portion of each of the end pieces 5 B of the settee or sofa is shaped or designed, as shown, so as to afford a projecting ledge or stop-like surface at b^2 , (see Fig. 2,) on which the table-bed proper of the article contacts and rests when turned into the vertical 10 position to adapt the article for use as a settee.

b^2 are two hinged arms of the sofa or settee, the turning of which into one or another position, according to the uses to which the 15 combination article may be adapted, will be presently further explained, while B^3 and B^4 are detachable or removable and replaceable covering-blocks adapted to cover over or hide from view, respectively, the protruding 20 track-wheels D and the protruding caster-wheels H when the game-table portion of the article is adjusted in its vertical position to constitute the back of the sofa or settee, each of said covering-blocks being provided with 25 headed pin-like devices which engage with the keyhole-apertures $e^7 f^7$, made in the bottom board a of the billiard-table bed.

When the two main portions of the article are set in the relative position seen at Fig. 1, 30 all the parts appear as they are shown at the right-hand end of said figure; but when it may be desired to transform the settee into a game-table the detachable covering-blocks B^3 and B^4 are detached, (as illustrated at the 35 left-hand end of said figure,) and each of the hinged arm-pieces b of the settee is turned over inwardly and downwardly into the position illustrated at the left-hand side of said figure, and with these hinged and removable 40 parts all in the conditions thus illustrated at the left-hand side of the figure the bed portion of the article, which constitutes the back of the settee, may then be oscillated about the axis of longitudinal shaft E in the proper 45 direction and to an extent sufficient to bring the bed portion of the article into a horizontal position and with its slightly-protruding grooved wheels D D and its small caster-wheels H H down into contact with the 50 track-rails G G, mounted on the top of the end portions B B of the settee, and with the parts thus adjusted or with the game-table portion thus turned down into a horizontal position the latter may be then pulled or 55 pushed sidewise in the direction indicated by the arrow at Fig. 3 until the parts shall have been brought to the relative position illustrated in said figure, the grooved track-wheels D D and the small caster-wheels H H 60 during this horizontal movement of the game-table portion of the article rolling along in contact with track-rails G G and with the bottom surface or portion of the game-table bed slightly elevated above and out of contact with the top surfaces of the said end por-

tions B of the sofa until the sliding or rolling movement of the bed portion shall have been completed, at which time the grooved wheels and the caster-wheels will have descended, respectively, into the two depressions g and g^2 of the track-rails, all as clearly seen at Fig. 4 of the drawings, so as to permit what was the back board of the settee to come down into perfect contact with and rest firmly upon the upper surfaces of the wooden end 70 portions B B of the sofa, by which latter the entire gravity of the game-table bed will then be solidly or rigidly supported, and when in this position each of the locking-pins must then be manipulated by hand, so as to operate as stops against the forward surfaces of the upturned portions G' of the metallic tracks, as seen at I, Fig. 4, to thus prevent any casual back movement or initial return movement of the thus adjusted table-bed on 75 top of its supporting devices. To change from the game-table back to the sofa, the locking-pins I must first be worked by hand to disengage them from the upwardly-projecting end portions G' of the track-rails, 80 (must each be pulled back into the position shown in dotted lines at Fig. 6,) after which the table-bed may be easily pushed or rolled backwardly in its horizontal condition by hand until the grooved wheels shall have 85 come into contact with the curved upward projections G' of the track-rails, whereupon by lifting up and moving backwardly in the arc of a circle the front side or edge of the table-bed A the latter may be very easily oscillated into the position seen at Fig. 1, and after this translation of the bed into its vertical position the blocks B^3 and B^4 may be 90 replaced to cover over and hide from view the protruding or exposed portions of wheels 95 D D and casters H H, the hinged arm-pieces b (that had been turned over when the sofa was to be changed to a table) being then 100 turned back again into the position seen at the right-hand side of Fig. 1. It will be understood that in thus making the transformation from table to sofa the blocks B^3 after 105 having been placed in position to cover the projecting peripheral portions of wheels D and with their dowel-pins in engagement 110 with the holes or apertures in bottom board a are locked in or permanently secured in 115 position by the turning over into position for use of the arm-pieces b of the sofa, the rear ends of which arm-pieces close down in front 120 of and against the outer vertical (lower end) portions of said covering-blocks. (See Fig. 1.) By having the rolling bed portion mounted 125 on wheels D D, that are located at points approximately midway between the two longer sides or edges of the bed A, the latter, it will be understood, is nearly balanced on its supporting track-wheels, and hence will offer 130 comparatively little resistance to the tipping or oscillating movement necessary to trans-

late the bed from the horizontal to the vertical position, and vice versa, by hand, no matter how heavy the bed may be, and this structural feature renders the piece of furniture 5 very easy of manipulation in effecting the transformations. It will, however, be seen that the wheels D D (and their shaft E) are not located exactly in the middle of the bed A, (widthwise of the latter,) under which ex- 10 act condition the tilting of the bed could be effected with still less hand-power applied; but, as arranged, comparatively little hand-power is necessary to work the parts, and under this arrangement I get the parts so relatively positioned (the distance of the grooved 15 wheels and caster-wheels at such distances from the axis of rotation of the bed) that in oscillating the bed A from its vertical down into its horizontal position the two caster-wheels H H will land in contact with the track-rails G slightly in advance of the necessary V-shaped rear portions of said rails (with 20 which the wheels D D engage) and so as to come down onto the flat or unribbed portions 25 of rails G, thus simplifying and rendering more mechanically correct and easier of manufacture and more desirable in operation the machine-work (or metallic working parts) of the piece of furniture.

30 Of course, while I have shown my invention carried into effect in a piece of furniture of what is known as the "mission" design, it may with equal advantage be carried out in a combination sofa and table of wholly a different style, in which all or parts of the sofa or 35 settee may be upholstered after any desired design, and it will be understood that while I have practiced my invention under the precise forms as to details shown many modifications or variations may be made without 40 departing from the novel principle of construction and mode of operation peculiar to my improved construction, the main features of which are based on the ideas of having the 45 translatable bed A mounted to oscillate about an axis of motion located approximately at the center of gravity of the bed widthwise and combining the bed and its supporting-wheels with horizontal immovable or rigid track-rails in such manner that 50 while the bed travels easily on said track-

rails (back and forth) horizontally it comes down into contact with the upper ends of the sofa arms or end pieces B B when it assumes its position of use for a table, so as to be 55 firmly and directly supported in this operative position by the upper ends of the sofa end pieces B B, as described.

Having now so fully described my improved construction of combined sofa-table 60 that those skilled in the art of making and familiar with the uses of such an article can readily make and use a piece of furniture embodying my invention, what I claim as new, and desire to secure by Letters Patent, is— 65

1. In a combined sofa, or settee and pool, or billiard table, the combination, with the seat and end portions of a settee, of a table bed portion provided with track-wheels; and track-rails mounted on top of the settee end portions, and on which said wheels travel; the combination being and operating so that when the bed shall have been rolled into its final position for use as a game-table, said bed will automatically come into contact with and be wholly supported by the upper ends of the settee end pieces, or portions; substantially as set forth. 75

2. In a combined sofa or settee and pool or billiard table, the combination, with the seat and end portions of a settee; and the translatable game-table and sofa-back portion of the piece of furniture, of track-wheels mounted on a shaft located in the said table portion; and track-rails mounted immovably on 80 the upper ends of the settee end pieces and formed with depressions, as specified; the combination being and operating so that, by the descent of the said track-wheels into the 85 said depressions of the track-rails, the bed will, in assuming its final position, for use as a game-table, come automatically, into contact with and rest solidly on top of the said settee end pieces; all substantially as set forth. 90

In witness whereof I have hereunto set my hand this 14th day of April, 1905.

J. N. MCINTIRE.
